UNITED STATES PATENT OFFICE.

FRANK E. TEN EYCK, OF AUBURN, NEW YORK, ASSIGNOR TO AIR DEVICE MANUFACTURING COMPANY, OF CHICAGO, ILLINOIS, A CORPORATION OF MAINE.

COMBINED PUMP AND STARTER FOR AUTOMOBILES.

1,184,270.

Specification of Letters Patent.

Patented May 23, 1916.

Original application filed June 12, 1914, Serial No. 844,611. Divided and this application filed September 14, 1914. Serial No. 861,556.

To all whom it may concern:

Be it known that I, FRANK E. TEN EYCK, a citizen of the United States, residing at Auburn, in the county of Cayuga and State 5 of New York, have invented certain new and useful Improvements in Combined Pumps and Starters for Automobiles; and I do hereby declare the following to be a full, clear, and exact description of the invention, such as will enable others skilled 10 in the art to which it appertains to make and use the same.

My invention consists in the novel features hereinafter described, reference being 15 had to the accompanying drawings which illustrate an embodiment of the invention selected by me for purposes of illustration, and the said invention is fully disclosed in the following description and claims.

20 Referring to the said drawings, Figure 1 represents a side elevation of my improved air pump and starter showing it operatively connected with the explosion engine of an automobile or other motor vehicle, a portion 25 of the dash board being indicated in section and the location of the air pressure gage and control mechanism for the hand operated control valve being also illustrated. Fig. 2 is a front end elevation of the apparatus shown in Fig. 1. Fig. 3 is a rear end elevation of the combined pump and starter detached, drawn to a slightly enlarged scale. Fig. 4 is a top plan view of the combined 30 pump and starter, a portion of the mechanism being indicated in section. Fig. 5 is a rear end view of a portion of the apparatus showing the distributor valve casing with the cover removed and the valve removed. Fig. 6 is a detail view of the distributor 35 valve showing the inner face thereof. Fig. 7 is a horizontal section on line 7—7 of Fig. 5 looking in the direction of the arrows. Fig. 8 is a side elevation partly in section of the hand operated control valve on the 40 dash. Fig. 9 is a front view of the valve casing with the cover removed, showing the valve in position. Figs. 10 and 11 are detailed views of the inlet and exhaust valves with which each cylinder of the combined 45 pump and starter is provided. Fig. 12 is 50

a detailed sectional view of one of the automatic valves with which each cylinder of the pump and starter is provided.

The object of my invention is to provide a convertible motor compressor adapted to 55 be operatively connected with an engine, which can be operated by the engine as a pump for the purpose of compressing and storing air or other motor fluid, and which can be operated by said compressed motor 60 fluid as a motor for the purpose of starting the explosion engine, that is to say, for the purpose of turning over the engine sufficiently to enable it to operate as an explosion engine under its own power. 65

The subject matter of this invention is a division of my former application for Letters Patent of the United States filed June 12, 1914, and given Serial No. 844,611.

70 In the accompanying drawings 1 represents the explosion or internal combustion engine, which in this instance is provided with four explosion cylinders 2, 3, 4, and 5. 6 represents the crank shaft which is provided with a sprocket wheel 7 by means 75 of which power may be transmitted to the combined pump and compressed fluid motor.

The engine as illustrated in Fig. 1 is mounted on the forward part of the chassis 80 of an automobile or other motor vehicle, the dash board of which is indicated at 8.

The combined pump and motor is shown 85 in Figs. 1 and 2 as located at one side of the engine and suitably supported in fixed relation thereto and it comprises a base portion 10 and a plurality of cylinders, three cylinders 11, 12, and 13, being shown in the embodiment illustrated in the drawings. Each of the cylinders is provided 90 with a piston and piston rod of ordinary construction (not shown) operatively connected in the usual manner with a crank shaft 14, which in this instance is provided with a pinion 15 having a broad face, said 95 pinion being in mesh with a gear wheel 16 mounted on a secondary shaft 17, journaled in bearings in the base 10 of the pump, and extending longitudinally through the same, said gear 16 being connected to the shaft 100

by a key 18 and being capable of sliding longitudinally on the shaft. Loosely mounted on the shaft is a hub or clutch member 19 provided with a clutch recess 20 to receive a clutch projection 21 which is preferably secured to the gear 16 and upon the hub or clutch member 19 is secured a sprocket 22 by means of a key or otherwise, which sprocket is connected by a sprocket chain 9 with the sprocket 7 on the crank shaft of the engine. I also provide automatic means for clutching the sprocket wheel 22 to the secondary shaft 17, in this instance by moving the gear wheel 16 endwise on the shaft 17 to interlock the clutch projection 21 and recess 20 (see Fig. 4) which mechanism includes a cylinder 23 provided with a piston 24 working therein, and piston rod 25 having a shoulder 26 for limiting its outward motion by engagement with the outer end of the cylinder, the said piston rod being provided with a yoke 27, engaging an annular groove on the hub of the gear wheel 16, and a retracting spring 28 being provided in this instance within the cylinder 23 and surrounding the piston rod 25 for returning the parts to normal position.

Each of the pump cylinders is provided with an inlet valve 30, one of which is shown in detail in Fig. 10, in this instance, provided with a spring seated valve, and the upper end of the pump cylinders, which are preferably formed as a single casting, are connected by a delivery passage 31, indicated in Fig. 11, and each engine cylinder is provided with an outlet valve indicated at 32 in Fig. 11, provided with spring pressed ball valve which opens to permit the air compressed in the cylinder to pass through the discharge passage 31. The discharge passage 31 communicates with a pipe 33 which is connected through the hand operated control valve hereinafter referred to with a storage tank indicated at 110 in Fig. 1, and I prefer to designate the pipe 33 as the pump line, for convenience of reference. 34 represents a branch line or by pass from the pump line or discharge passage 31 to the clutch operating cylinder 23 (see Fig. 4), for supplying compressed air to the cylinder 23 to operate the clutch.

From the foregoing description of the apparatus, it will be apparent that if the tank is partially charged with air and the control valve hereinafter described is placed in such a position as to open communication between the pump line 33 and the tank, the back pressure from the tank will pass to the by-pass 34 and actuate the piston 24, thus clutching the gear 16 to the engine driven sprocket 22, and if the engine is running, the pump will be immediately actuated to compress air and force it back into the tank until the desired pressure is obtained, when

the pump line will be cut off from the tank 65 and the spring 28 will automatically disconnect the pump from the engine.

Each of the pump cylinders is provided with an automatic pressure operated valve 35, one of which is shown in detail in Fig. 12. This valve comprises a body 36, which may be cast integrally with the pump cylinder as shown in Figs. 1, 2, 3 and 4, or may be formed separately and screwed to the cylinder, as shown in Fig. 12 provided with a valve seat 37, a needle valve or stem valve 38, adapted to slide in a suitable guiding means provided in connection with the casting 36, in this instance a threaded sleeve 39, the valve stem being provided with a piston 40 working in an extension chamber 41 and provided with a spring 42, which normally holds the valve seated. The casting 36 is provided with an inlet aperture 43 to which a pipe may be connected, and the extension chamber is provided below the piston with an inlet 44 to which a pipe can be connected, for the purpose of introducing compressed air to operate on the lower face of the piston 40 and raise the valve off of 90 its seat. The relief chambers 45 below the pistons 40 in all of the automatic valves 35 are connected with a by pass 46 in any desired way, in this instance by connecting pipes 46^a (see Fig. 4), so that the pistons 40 may be simultaneously actuated by compressed air entering through the pipe or by pass 46, as hereinafter explained.

At one end of the pump mechanism I provide what I term the distributor casing, indicated at 50 and best shown in Figs. 5 and 7. This casing is conveniently formed on the end of the pump base and a reduced portion 14^a of the pump crank shaft extends into it and is provided at its end with a 105 pair of apertures 14^b. The casing 50 is closed by a cap 51 and within the casing is a rotary disk valve 52, which is preferably provided with pins 53 for engaging the apertures 14^b in the crank shaft and connecting the disk to the crank shaft. The inner face of the disk is ground to fit against the inner face of the recess formed within the casing 50 and the disk is provided with a segmental slot 54 and with a segmental 110 recess 55 on its inner face, having a short passage 56 extending therefrom and communicating with a central passage 14^c in the crank shaft 14, which terminates at one side of the shaft at some convenient point 120 inside of the casing to take care of the exhaust when the pump is used as a fluid pressure motor as hereinafter described. It will be understood that the casing 10 of the pump will be provided with the usual 125 breathing aperture 10^a.

The bottom face of the recesses within the casing 50, against which the valve disk 52

rotates is provided with three ports 11^a, 12^a, 13^a, from which passages extend which are connected by pipes 11^b, 12^b, and 13^b, respectively, with the casing 36 of the automatic 5 valve on the pump cylinders 11, 12, and 13, respectively. The relation of the segmental aperture 54 and the segmental recess 55 of the valve disk 52 are such that during the 10 rotation of the disk, compressed motive fluid will be admitted to the pump cylinders 11, 12, 13, in rotation, to actuate the same through the aperture 54 while the cylinders will be permitted to exhaust the expanded motor fluid which returns through 15 the same pipes, through the recess 55, to the exhaust aperture 14^c in the shaft or the exhaust might be delivered in any other desired manner to the atmosphere. The interior 20 of the casing 50 communicates with a lateral passage 57 in a boss 58 on the end of the pump casing, which boss is provided with an inlet aperture 59 connected by a pipe 60 with the compressed air tank through the hand operated control valve 25 hereinafter described, the pipe 60 being termed for convenience, the starter pipe line. The boss 58 is also provided with a lateral aperture 61 to which is connected the by-pass pipe 46 before referred to, which 30 communicates with the relief chambers of all the automatic valves 35 for the purpose of lifting the valves off their seats, as before stated.

It will now be seen that if the connection 35 between the pump line 33 and the tank is cut off, and communication between the starter pipe line 60 and the tank is established, compressed air from the tank at high pressure will be delivered through the starter 40 pipe line to the boss 58 and will pass thence through the pipe 46 to the relief chambers of the several automatic valves, thus opening the valves 38 and the motor fluid will also pass through the passage 57 into the distributor 45 50 and through the slot 54 and the particular port which is uncovered at the time, to one of the pump cylinders through the automatic valve 35 thereof, thereby imparting motion to the piston in the said 55 valve and starting the pump mechanism which then acts as a motor. The rotation of the disk 52 will distribute the compressed fluid to the pump cylinders in rotation as before stated, and the cylinders will exhaust 60 in the manner described so that a rapid rotation of the shaft 14 is effected by the device, acting as a motor. The introduction of compressed air into the pump cylinders will simultaneously open the outlet valves 65 70 75 80 85 90 95 100 105 110 115 120 125 32 thereof and permit a portion of the compressed fluid to pass into the passage 31, which being in communication with the by-pass 34 and the trunk line 33 being closed, as before stated, will effect automatically

the operation of the piston 24 in the cylinder 65 23 and clutch the wheel 16 to the sprocket wheel 22 connected with the engine, thereby imparting motion from the crank shaft of the starter to the engine shaft, as will be readily understood.

For convenience in applying my invention to the engines of automobiles and other motor vehicles so that the mechanism can be controlled from a point adjacent to the steering wheel or steering shaft, I employ a controlling valve which is illustrated in detail in Figs. 8 and 9, and which is also shown in Fig. 1. This control valve comprises a valve casing 75 which may be conveniently mounted upon the steering sleeve 76 through 70 which the steering shaft 77 provided with the usual steering wheel 78, extends. This casing is provided on the rear face with a removable cover 75^a preferably provided with a hollow boss 75^b which is connected 80 at one end with a pipe 80 extending to the tank 110, which may be of any desired form or size and which is preferably provided with the usual cut off valve by which it can be hermetically closed, so as to disconnect 85 it from the pipe line and prevent leakage when the apparatus is left for a considerable time, in order that there always may be a reserve of compressed fluid in the tank. The other end of the passage in the 90 boss 75^b is connected by a pipe 81 with a pressure gage 82, which preferably has its dial so located that it can be seen by the operator. The valve casing 75 is provided on its interior face with two ports 83 and 84 communicating with lateral passages which are connected respectively with the starter pipe line 60 and the pump line 33. The valve casing 75 is also provided with an oscillating disk valve 90 which is provided with two apertures 91 and 92 adapted 100 the one to be brought into registration with the port 84, and the other into registration with the port 83, and the disk valve is provided with lateral projections 93 at opposite sides, adapted to engage a pin 94 and stop the valve when it is in one or the other of its operative positions, while in a central position between the two operative positions, both of the ports 83 and 84 will be 105 closed by the solid portion of the disk as clearly shown in Fig. 9. For convenience the oscillating valve disk 90 is provided with a valve stem 95 extending out through the front of the casing and provided with an operating handle 96 and pointer 97 which is placed over the dial 98, and the dial will be marked with an indication for "off" or neutral position and also for the "pump" and "starter" positions. The control valve 110 115 120 125 may be provided with a suitable clamp as indicated at 75^a for attaching it to the sleeve 76 of the steering head and the shaft 95 may

also be supported at its outer end in a suitable bearing 99 provided with a clamp 100 for engaging the steering head and holding the shaft in proper position. I also prefer 5 to employ a spring indicated at 100 in Fig. 8 for maintaining the oscillating disk 90 in close engagement with the inner face of the valve casing 75.

The various parts of the apparatus having now been described, it will be understood that if the engine is running and it is desired to compress a quantity of air into the tank, and store the same, the operator will throw the handle 96 to the indicated 10 position for operating the combined pump and starter as a pump, which moves the control valve disk 90 into position to bring the aperture 91 into communication with the port 84, the back pressure of air already 15 contained in the tank will immediately exert itself through the pump line 33 as before described and through the by pass 34 so as to actuate the piston 24 and connect the gear 16 with the sprocket 22, thereby transmitting 20 power from the engine to the pump shaft 15 and driving the pistons thereof so as to compress air therein, which is discharged through the outlet valves 32, the passage 31 communicating therewith, and 25 back through the pump line 33, ports 84 and 91 and tank pipe 80, to the tank, the accumulated pressure being indicated on the gage 82. When the gage reaches the desired point, say 200 lbs., the operator will 30 move the handle 96 to the neutral position, thus shutting the pump line at the control valve and the loss of pressure in the pump line which follows will permit the spring 28 to disconnect the clutch mechanism 20—21, 35 and disconnect the pump from the engine. Supposing that the engine is at rest, and it is desired to start the engine, the operator will move the handle 96 into the position to bring the valve port 92 into registration 40 with the port 83 and establish communication between the tank and the starter pipe line 60, and simultaneously establishing communication between the tank and by pass 46 leading to the relief chambers of 45 the automatic valves 35 of the pump cylinders. The compressed air from the tank passing through the starter pipe line 60 passes to the boss 58 and to the distributor before described. The admission of the 50 compressed air through the distributor to the appropriate pump cylinder, will immediately start the pump, which acts as a motor, and the admission of compressed air to any pump cylinder transmits the pressure 55 of the motor fluid, as before stated, through the exhaust valves 32 of the pump and the passage 31 to the by pass 34 and cylinder 23, causing the piston 24 to act and again connect the gear wheel 16 with the engine. 60

This enables the pump mechanism acting as 65 a starter to move the engine shaft and start the engine, after which the handle 96 is thrown to the neutral position and the supply of compressed fluid to the pump and engine cylinders is cut off, and the engine 70 will continue to operate under its own power. The spring 28 withdraws the clutch member 21 from the recess 20, permitting the combined pump and starter to be brought to a condition of rest. 75

In order to quickly relieve the pressure in the pump line 33 whenever the control valve is moved to neutral position, so as to permit the spring 28 to retract the piston 24 and withdraw the clutch member 21, I prefer 80 to provide the control valve with special means for relieving the pressure in the pump line, which consists in this instance of the following instrumentalities. The valve casing of the control valve is provided with 85 a small relief passage 75° extending from the bearing aperture of the valve shaft 95 to the atmosphere. The valve shaft is provided with a recess 95° adapted to be brought into registration with the relief 90 passage 75° when the valve 90 is in neutral position and the valve 90 is provided with a recess 90° in its face, communicating with the shaft recess 95°, and extending outwardly far enough so that when the valve 95 is in neutral position, this recess 90° will extend over the port 84, which communicates with the pump pipe line 33. The result of this construction is that as soon as the valve 90 is turned to neutral position from either 100 the pump position or starter position, it will establish communication between the pump pipe line 33 and the atmosphere through the valve recess 90°, shaft recess 95°, and relief passage 75°, thus permitting the pump line 105 to immediately relieve its pressure, thereby relieving the pressure in the cylinder 23 behind the piston 24, and permit the spring 28 to quickly withdraw the clutch member 21. 110

When the control valve is in neutral position and the relief passage 75° in communication with the port 84, the reduction of pressure in the pump line 33 just described, permits the compressed fluid in the particular cylinder of the pump and starter which at the moment is in communication with the main distributor 51 (and one or other of said cylinders is at all times in communication with the distributor), to exhaust through the exhaust valve into the pump line 33 and thence to the atmosphere through the relief passage 75°. This relieves the compression in the starter line 60 extending to the distributor 51 and in the by 120 pass 46 communicating with the actuating cylinders of the auxiliary inlet valves of the pump 35 of the pump and starter, thus 125

permitting the said valves to close, and quickly restoring the entire apparatus to normal position as soon as the controlling valve is returned to neutral position.

5 When the combined pump and starter is operated from the engine as before described to compress air into the tank if the operator should neglect to disconnect the pump, by throwing the controlling valve to neutral 10 position when the desired pressure, say 200 lbs., is reached in the tank, the springs holding the automatic valves 38 on their seats, which are adjusted to resist any pressure below that desired in the tank, will there- 15 after yield and permit an escape of compressed air from the pump cylinders. When this occurs the lifting of the valves, 38, off of their seats, 37, will establish communication through the passage, 43, of each 20 valve casing and the connecting pipes or passages, 11^b, 12^b and 13^b with the distributor ports 11^a, 12^a, and 13^a, and as these several ports are brought into communication with the exhaust recess, 55, of the rotary distributor valve the compressed air will escape through the said recess and passage, 56, to the exhaust passage, 14^c, in the pump shaft, and thence to the atmosphere. The valves 35 will thus act as safety valves 30 to prevent the accumulation of too great pressure in the tank.

What I claim and desire to secure by Letters Patent is:—

1. The combination with a pump mechanism provided with a cylinder and a piston working therein, inlet and outlet valves for the cylinder, a storage tank, and a pump line extending from the outlet valve to the tank, said cylinder being provided with an auxiliary air inlet, of a starter line for connecting said auxiliary air inlet with the tank, a normally closed valve controlling said auxiliary inlet, an actuating cylinder and piston for opening said valve, a by-pass 35 from said starter line to said actuating cylinder, a manually controlled valve mechanism for shutting off communication between the tank and the pump line and starter line, and means for relieving pressure in the starter line when its communication with the tank is closed, to permit the quick closing of the auxiliary inlet valve.

2. The combination with a pump mechanism provided with a cylinder and a piston working therein, inlet and outlet valves for the cylinder, a storage tank, and a pump line from the outlet valve to the storage tank, said cylinder being provided with an auxiliary air inlet, of a normally closed 55 valve for said auxiliary air inlet, an actuating cylinder and piston for opening said valve, a starter line for connecting the auxiliary air inlet with the tank, and a by-pass from said connection to said actuating cyl-

inder for opening the auxiliary inlet valve, 65 a manually operated valve mechanism interposed in said pump and starter lines between the tank and the outlet valve of the pump and between the tank and the auxiliary inlet valve, and constructed to close 70 both of said lines when in neutral position, said valve mechanism being provided with a relief aperture adapted to be brought into communication with the pump line when the valve is in neutral position to relieve the ac- 75 cumulated pressure in the starter line, through the outlet valve and pump line and permit the auxiliary inlet valve to close quickly.

3. The combination with a pump mechanism provided with a cylinder and a piston working therein, inlet and outlet valves for the cylinder, a storage tank, and a pump line extending from the outlet valve to the tank, said cylinder being provided with an auxiliary air inlet, of a starter line for connecting said auxiliary air inlet with the tank, a normally closed valve controlling said auxiliary inlet, an actuating cylinder and piston for opening said valve, a by-pass 80 from said starter line to said actuating cylinder, a valve casing interposed in the pump line and in the starter line, a valve in said casing adapted to close both lines when in neutral position and constructed to open one 85 of said lines only at a time, said valve casing being provided with a relief aperture, and said valve being provided with a relief passage adapted to connect the pump line with said relief aperture when the valve is in neutral position, whereby accumulated pressure is relieved in the pump line and through the outlet valve of the cylinder in the starter line, and said by-pass, to permit the auxiliary 90 inlet valve to close quickly.

4. The combination with a pump mechanism provided with a cylinder and a piston working therein, inlet and outlet valves for the cylinder, a storage tank, and a pump line extending from the outlet valve to the tank, said cylinder being provided with an auxiliary air inlet, of a starter line for connecting said auxiliary air inlet with the tank, a normally closed valve controlling said auxiliary inlet, an actuating cylinder and piston for opening said valve, a by-pass 100 from said starter line to said actuating cylinder, an actuating shaft connected with the pump and piston, a clutch for connecting said actuating shaft with the shaft of a prime motor, an actuating cylinder and piston for said clutch, a by-pass from the pump line to said actuating cylinder, controlling valve mechanism interposed in both the pump line and starter line, and provided with means for relieving the 105 pressure in the pump line when the valve mechanism is in neutral position, whereby the opening of a communication between the 110

tank and either the pump line or starter line will operate the clutch actuating piston, and whereby when the valve mechanism is in neutral position the pump line and starter line will be relieved to permit the quick closing of said auxiliary valve and the return movement of the clutch actuating piston.

5. The combination with a multi-cylinder pump and motor, each cylinder being provided with inlet and outlet valves, a storage tank, connections from the outlet valves to the storage tank, each of said cylinders being provided with an auxiliary inlet aperture, a normally closed valve for each of said apertures, and a piston and cylinder for controlling each of said valves, of a distributer operatively connected with the pump shaft, connections from the distributer to each of said auxiliary valve-controlled cylinder inlets, a connection from the tank to the distributer, and a by pass connecting the tank with the cylinders of said auxiliary valves for opening all of said valves simultaneously and permitting the admission of pressure fluid to all of said cylinders under the control of the distributer when the apparatus is used as a motor.

6. The combination with a multi-cylinder pump and motor, each cylinder being provided with inlet and outlet valves, a storage tank, a pump line connecting the outlet valves to the storage tank, each of said cylinders being provided with an auxiliary inlet aperture, a normally closed valve for each of said apertures, and a piston and cylinder for controlling each of said valves, of a distributer operatively connected with the pump shaft, connections from the distributer to each of said auxiliary valve-controlled cylinder inlets, a starter line connecting the tank to the distributer, and a by pass from the starter line connecting the tank with the cylinders of all of said auxiliary valves for opening the same and permitting the admission of pressure fluid under the control of the distributer, when the apparatus is used as a motor, clutch mechanism for connecting the crank shaft of the combined pump and motor with a prime motor, a cylinder and piston for operating said clutch, a by pass from the connection communicating with the outlet valves of the pump to said clutch operating cylinder, open at all times for automatically throwing said clutch into operative position by accumulated pressure in the tank when the device is to be operated as a pump by the prime motor, or as a motor and controlling valve mechanism interposed between the pump line and starter line and the tank for starting the prime motor.

7. The combination with a multi-cylinder pump and motor, each cylinder being pro-

vided with an inlet and outlet valve, a storage tank, a pump line connecting the outlet valves to the storage tank, each of said cylinders having an auxiliary inlet, an auxiliary normally closed valve for each of said inlets, a piston and cylinder for opening each of said valves, a distributer comprising a valve casing having a port for each of said cylinders, and a connection from each of said ports to one of the auxiliary valve-controlled inlets of said cylinders, a rotary valve in said valve casing operatively connected with the crank shaft of the pump and motor and provided with an inlet aperture and an exhaust aperture to coöperate with said ports, a connection from the tank communicating with said inlet apertures in the valve, an exhaust passage communicating with the exhaust aperture in the valve and a by pass for connecting the tank with the actuating cylinders for said auxiliary valves, for opening them when the apparatus is to be used as a motor.

8. The combination with a pump mechanism provided with a cylinder, a single acting piston working therein, and inlet and outlet valves for the cylinder, said cylinder being provided with an auxiliary inlet, of a valve normally closing said auxiliary inlet, a cylinder and piston for controlling said valve, a storage tank, a pump line connecting the tank with the outlet of the cylinder, a distributer operatively connected with the motor shaft, a starter line connecting the tank to the distributer, a connection from the distributer to said auxiliary inlet, a by-pass connecting the starter line with the cylinder for controlling the auxiliary inlet valve, and a manually operated controlling valve interposed in the starter line between the tank and the distributer and said by-pass and provided with a relief aperture communicating with the atmosphere when the said controlling valve is in inoperative position, for quickly relieving pressure in said by-pass to permit the auxiliary inlet valve to close.

9. The combination with a pump mechanism provided with a cylinder and piston working therein, inlet and outlet valves for the cylinder, said cylinder being provided with an auxiliary inlet, of a valve normally closing said auxiliary inlet, a cylinder and piston for controlling said valve, a storage tank, a pump line connecting the tank with the outlet of the cylinder, a distributer operatively connected with the motor shaft, a starter line connecting the tank with the distributer, a connection from the distributer to the auxiliary inlet of the pump, a by-pass connecting the starter line with the cylinder for controlling the auxiliary inlet valve, clutch mechanism for connecting the crank shaft of the combined pump and motor with

a prime motor, a cylinder and piston for operating said clutch, a by-pass from said cylinder to the pump line open at all times, for establishing communication between said cylinder and the storage tank, and a controlling valve interposed in the connections between the tank and the said distributor and said by-passes, said valve being provided with a relief port adapted to establish communication simultaneously between said by-passes and the atmosphere when the valve is

5
10

in inoperative position, to quickly relieve pressure in the cylinders for operating said clutch mechanism and the controlling valve for the auxiliary air inlet of the pump 15 cylinder.

In testimony whereof I affix my signature, in the presence of two witnesses.

FRANK E. TEN EYCK.
